UNITED STATES PATENT OFFICE.

WILLIAM J. BUTLER, OF CRANSTON, RHODE ISLAND, ASSIGNOR TO HENRY LEDERER & BRO. INC., OF PROVIDENCE, RHODE ISLAND, A CORPORATION OF RHODE ISLAND.

CIGAR LIGHTER.

Application filed February 23, 1927. Serial No. 170,223.

This invention relates to improvements in a pocket cigar lighter of the pyrophoric type; and has for its object to provide such a device with a more practical and efficient construction of sparking mechanism than those heretofore constructed.

A further object of the invention is to provide a spark wheel and a different thumb wheel both in a single unit and to 10 secure this unit in operating position by a screw threaded trunnion, whereby the unit may be removed for cleaning purposes and readily replaced by a fresh one when the unit becomes worn and its efficiency impaired.

With these and other objects in view, the invention consists of certain novel features of construction, as will be more fully described, and particularly pointed out in 20 the appended claims.

In the accompanying drawings:

Figure 1 is a perspective view of a cigar lighter with my improved sparking device mounted thereon.

25 Figure 2 is a sectional elevation of the device through the sparking mechanism.

Figure 3 is a fragmental portion of the reservoir sectioned through the wick tube.

30 Figure 4 is a fragmental portion of the reservoir showing the sparking mechanism, also showing the extinguishing cap in section.

Figure 5 is an enlarged sectional view of 35 the sparking wheel and its separate operating thumb wheel.

Figure 6 shows the trunnion screw for the spark and thumb wheels.

It is found in practice that in the manufacture of pocket cigar lighters of the pyrophoric type, it is advantageous to construct 40 the spark wheel and the thumb wheel in sleeve form as a single unit but substantially spaced from each other, as such a unit with both wheels may be made in a single operation and of minimum expense as a so-called "screw machine product" after being drilled 45 the unit as a whole may be subjected to the required hardening operation. In assembling the parts this unit is secured in position by a threaded trunnion which is screwed into the reservoir and which may be readily removed for the purpose of removing the unit to be cleaned or to be exchanged for a 50 fresh one when the ribs of either the wheel engaging the pyrophoric material or those

on the thumb wheel become worn and ineffective. Then again, it is found that by spacing the thumb wheel a substantial distance from the spark wheel and forming the thumb wheel of a diameter substantially 60 greater than that of the spark wheel, the thumb of the operator when engaging the thumb wheel will be prevented from contacting with and soiling the spark wheel; and the following is a detailed description of the 65 present embodiment of my invention and showing one means by which these advantageous results may be accomplished:

With reference to the drawings, 10 designates the fuel reservoir of the device which 70 may be formed of any desired size and of any suitable material, the same being preferably constructed to contain a portion of absorbent material 11 saturated with an inflammable substance such as alcohol or the like and 75 into which material a wick 12 extends through its supporting tube 13 which projects above the upper surface of the reservoir. Also, there is mounted on the upper wall 14 of this reservoir a tube 15 for receiving a pyrophoric material which is supported in a holder 16, the boss 17 of which is herein shown as being riveted at 18 in this upper plate 14. At one end of this tube is 80 slidably mounted, the flint 19 or other suitable pyrophoric material which is pressed 85 outwardly by a spring 20, the opposite end of the spring being arranged to abut against an end of the adjusting screw 21 whereby the working friction of the flint on its spark 90 wheel may be adjusted.

In order to strike a spark on the flint or pyrophoric material and transfer it to the wick, I have provided a sparking unit which 95 comprises a sleeve or tubular member 21 having a vertically corrugated abrasive wheel 22 at its upper end, and a correspondingly corrugated thumb wheel 23 near its lower end, the latter wheel being of a diameter substantially greater than that of the 100 abrasive wheel. These two wheels are separated a substantial distance from each other on the sleeve and as the thumb wheel is also much larger than the spark wheel the thumb of the operator is prevented when engaging 105 the thumb wheel from coming in contact with the spark wheel and so prevent the spark wheel from becoming soiled and ineffective by such contact, and prevent the finger from becoming injured by contact 110

with the sharp teeth on the sparking wheel, and also prevent abrasion of the thumb by the sharp cutting surface of the spark wheel.

It is also found of advantage to be able to 5 remove this sparking unit for cleaning purposes and for replacing the same with fresh wheels when the effectiveness of the corrugations in either the thumb wheel or the spark wheel has become worn; and to accomplish 10 this in a simple and effective way, I have provided an enlargement 24 on the upper plate 14 having a threaded opening therein, and I have provided a trunnion or bearing member 25 which fits the bore of the spark- 15 ing unit or sleeve and is screwed into the enlargement 24 by which means the sparking unit is rotatably supported upon the reservoir, the lower wheel being in position to be readily engaged by the thumb of the operator 20 to rapidly rotate the spark wheel through the sleeve and transfer a shower of sparks from the flint or pyrophoric element 19 to the wick 12.

In order to extinguish the flame from the 25 wick, I have mounted a cup member 26 on the free end of the arm 27, which arm is pivoted at 28 in the bifurcated post 29, the pivoted portion of this arm being flattened on three sides whereby it may be engaged 30 by the spring-pressed detent pin 30 to be held either in its closed position, in its upright position or in its completely thrown back position all as illustrated in full and dotted lines in Figure 3.

35 By my improved construction of sparking unit the same may be formed with both the spark wheel and the thumb wheel of an integral piece of metal in sleeve form, the two being connected together as a unit may be 40 handled as a single unit, the tempering, finishing and assembling operations and by being retained in position by a removably threaded trunnion this unit after having become worn and slightly ineffective may be 45 readily replaced by a fresh unit which will renew the operating efficiency of the device.

The foregoing description is directed solely towards the construction illustrated, but I desire it to be understood that I reserve the privilege of resorting to all the mechanical changes to which the device is susceptible, the invention being defined and limited only by the terms of the appended claims.

55 I claim:

1. In a cigar lighter, a fuel reservoir car-

rying a wick tube having a wick therein, a pyrophoric tube, a spark wheel and thumb wheel unit in sleeve form, said two wheels being spaced apart and formed integral and of a single piece of metal, and a spring pressed pyrophoric material in the tube in engagement with the spark wheel whereby an igniting spark is carried from the pyrophoric material to the wick when the spark wheel is operated through a rapid rotation of the thumb wheel.

2. In a cigar lighter, a fuel reservoir carrying a wick tube with a wick therein, a pyrophoric tube, a pyrophoric friction wheel and thumb wheel in sleeve form, said two wheels being spaced apart and operatively connected together to form a single unit having a trunnion receiving hole through it, an internally threaded enlargement carried by the reservoir, and a trunnion member screw threaded at one end into said enlargement and on which said unit is rotatably mounted.

3. In a cigar lighter, a fuel reservoir carrying a wick and wick tube, a pyrophoric tube, a pyrophoric friction wheel and thumb wheel, said two wheels being spaced apart and formed of a single integral unit having a trunnion receiving hole through it, an internally threaded enlargement carried by the reservoir, and a trunnion member screw threaded at one end into said enlargement and on which said unit is rotatably mounted to be readily removed, said thumb wheel being of a diameter substantially greater than that of the spark wheel and removed from the spark wheel a substantial distance to serve as a guard and prevent the operator's thumb from contacting with the spark wheel.

4. In a cigar lighter, a fuel reservoir, a wick extending from said reservoir, a pyrophoric tube, a trunnion extending from and supported at one end only by said reservoir, a spark wheel and thumb wheel lying in parallel planes both above the reservoir and connected to function together and mounted on said trunnion, pyrophoric material in said tube and a spring pressing said pyrophoric material into engagement with said spark wheel whereby an igniting spark is carried from the pyrophoric material to the wick when the spark wheel is operated by a rapid rotation of the thumb wheel.

In testimony whereof I affix my signature.

WILLIAM J. BUTLER.
